 Servel, Inc., New York, N. Y., a corporation of
 Delaware

Application May 20, 1937, Serial No. 143,814

3 Claims. (Cl. 20—4)

This invention relates to insulation material and a method of installing or applying same, and is concerned primarily with the insulation of refrigerator and like cabinets having spaced inner and outer walls between which insulation material is inserted.

The invention, although of unusual simplicity, provides a number of important advantages, among which may be mentioned a simplified and more efficient insulating operation, particularly with respect to refrigerator and like cabinets; elimination of uninsulated spaces and crevices or cracks that would otherwise remain empty; the ability to carry out the insulating operation without the necessity of subsequent filling or stuffing of unfilled spaces with mineral wool or other similar material; and generally a more complete and uniform insulation of the spaces between the walls to be insulated.

With the foregoing and other objects and advantages in view, the invention consists in the preferred construction and arrangement of parts and the method of carrying out the insulating operation which will be more fully hereinafter described and claimed.

Generally stated, the present method of applying insulation between spaced walls to be insulated, such as between the inner and outer walls of refrigerator and like cabinets, consists in compressing a certain amount of compressible insulating material into block or other suitable form approximating the shape and area of the space to be insulated; packaging or binding the compressed insulation material by means of an adhesive substance or covering which will subsequently let loose or release the compressed insulation upon being subjected to a condition or agent which will nullify or destroy the adhesive or binding properties of the substance or covering such as a heating, drying, or a chemical action; then installing the compressed blocks of insulation in the said space, and thereafter subjecting the bound or packaged insulation to the appropriate condition or agent to thereby cause the adhesive or covering to release the compressed material, permitting the latter to expand and fill the space to be insulated.

In the drawing:

Fig. 1 is a view in front elevation of a refrigerator cabinet with the walls partly broken away to show the insulation therebetween, the blocks of insulation in this figure being shown compressed to facilitate their application or insertion between the walls of the cabinet;

Fig. 2 is a view similar to Fig. 1 but showing

the blocks of insulation after the adhesive which binds the same has been caused to release the insulation, permitting it to expand and fill the space between the refrigerator walls;

Figs. 3 and 4 show different types of insulation blocks for carrying out the present improved insulating method.

First referring to Figs. 1 and 2, a refrigerator cabinet is generally indicated at C and has a door D and a food compartment F. The outer casing or wall of the refrigerator is indicated at 10 and the inner wall or liner which defines the food compartment at 11, these walls being spaced from one another to permit the application or installation of insulating material therebetween.

Referring now to Figs. 3 and 4, these figures illustrate blocks of insulation material which are compressed ready for insertion in the space between the walls 10 and 11. In Fig. 3, the insulation block comprises compressible insulation material 12, such as balsam wool or the like whose individual fibers are more or less resilient. Insulation material 12 is packaged or bound by a wrapper 13 of paper or the like, the joined edge portions 14 of which are sealed by a suitable adhesive having, for example, a definite melting point. The wrapper or container 13 may be filled or stuffed with the insulation material and sealed at a temperature below the melting point of the adhesive. The dimensions or size of the respective blocks should be such as will permit ready insertion in the space to be insulated. After the blocks have been inserted in the said space, or spaces, the adhesive is subjected to a temperature such as will cause it to melt and release the sealed portion of the wrapper, thereby permitting the insulation material to expand and fill the said space.

In Fig. 4 the insulation material 12a is held compressed or bound by a covering 13a of suitable material having a certain predetermined melting point, so that after the block is inserted in the space to be insulated, the block or cabinet as a whole may be subjected to a temperature such as will cause the covering to melt and permit the insulation to expand.

This binding or covering could also be of a material such as would be dissolved by a drying or a chemical action. During assembling or packaging of the insulation, it will of course be understood that the temperature of the room or other characteristics which affect the binding or adhesive properties of the material used to hold the insulation in compressed form are such as

will be below the melting or dissolving point of the said material.

In applying a heating or other melting or dissolving agency, the entire cabinet may be subjected to the agency or the latter may be applied locally. For instance, the refrigerator cabinets may be warmed or baked after their assembly, or after the blocks are inserted, the melting or releasing agent could be applied directly to the blocks, or to the spaces around the same. If an adhesive or binding substance having a melting or dissolving point at or below room temperature is selected, the block or container therefor may be chilled and the assembling operation conducted at temperatures below room temperature.

There are numerous other methods which could be adopted in packaging or causing the insulation material to adhere or remain in compressed form until subjected to a releasing operation. For example, the entire material or a portion thereof could be impregnated or coated with a suitable adhesive or cement having the desired characteristics whereby when it is subjected to a temperature or other condition or agent, it will release the insulation and permit the latter to expand. The essence of the invention resides in the use of insulation material of a compressible and expandible nature and a binding substance therefor which will release the material when subjected to some condition or agent affecting the adhesive or binding properties of the substance.

Obviously, in selecting the adhesive or binding agent, any possible effect it may have on the insulating properties of the insulating material should be taken into consideration.

It will be understood that certain variations in structure and method of procedure may be adopted within the scope of the invention as defined by the appended claims.

I claim:

1. A method of insulating a space within a wall structure, which includes the following steps: compressing and confining insulating material in a wrapper to form a package, securing said wrapper with the aid of a binding agent to retain said

package in a compressed state, said wrapper being adapted when released to permit the expansion of said insulating material to fill said space; inserting said package into said space; destroying the binding property of said binding agent while said package is in said space, whereby said insulating material will be released from its compressed state so that it will expand to fill said space, and closing said space.

2. A method of insulating a space within a wall structure, which includes the following steps: compressing and confining insulating material in a wrapper to form a package similar in shape to said space but less in size than said space, securing said wrapper with the aid of an adhesive agent to retain said package in a compressed state, said wrapper being adapted when released to permit the expansion of said insulation to fill said space; the major portion of the interior of said package being substantially free of said adhesive agent, inserting said compressed package into said space; closing said space; and subsequently destroying the adhesive property of said adhesive agent whereby said insulating material will be released from its compressed state so that it will expand to fill said space.

3. A method of insulating a space bounded by wall structure, which includes the following steps: compressing and confining insulating material in a wrapper to form a package, securing said wrapper with the aid of a binding agent to retain said package in a compressed state, said wrapper being adapted when released to permit the expansion of said insulating material to fill said space; said binding agent having its binding property destroyable by a predetermined temperature, inserting said compressed package into said space while at a temperature other than said predetermined temperature; destroying the binding property of said binding agent by subjecting said package in said space to said predetermined temperature whereby said insulating material will be released from its compressed state in said package so that it will expand to fill said space, and closing said space.

WALTER A. KUENZLI.
